UNITED STATES PATENT OFFICE

THEODORE JOHNSON, OF ERIE, PENNSYLVANIA, ASSIGNOR TO JOHNSON METAL
PRODUCTS CO., OF ERIE, PENNSYLVANIA

OPERATOR FOR CASEMENT WINDOWS

Application filed January 8, 1929. Serial No. 331,124.

This invention relates to operators for casement windows and it is an object of the invention to provide a device of this kind which, when in applied position, offers no undue hindrance or obstruction to the application of a screen to the casement frame.

The invention also has for an object to provide a device of this kind whereby the window may be readily adjusted from fully closed to fully open position or vice versa and to desired points therebetween, and means for effectively locking the window in its desired adjustment.

Another object of the invention is to provide an operator of this kind which, when operated to move the window from its fully closed position, serves to provide a leverage action to facilitate such initial movement.

The invention consists in the details of construction and in the combination and arrangement of the several parts of my improved operator for casement windows whereby certain important advantages are attained and the device rendered simpler, less expensive and otherwise more convenient and advantageous for use, as will be herein-after more fully set forth.

The novel features of my invention will hereinafter be definitely claimed.

In order that my invention may be better understood, I will now proceed to describe the same with reference to the accompanying drawings, wherein:

Figure 1 is a view in top plan with a portion broken away illustrating an operator for a casement window constructed in accordance with an embodiment of my invention, the associated portions of the frame and window being diagrammatically indicated by broken lines;

Figure 2 is a view in elevation of my improved operator as herein embodied unapplied;

Figure 3 is a sectional view taken substantially on the line 3-3 of Figure 2, the adjacent portions of the window and frame to which the device is applied together with the associated screen being also shown in section;

Figure 4 is a sectional view taken substantially on the line 4-4 of Figure 2;

Figure 5 is a view in top plan of the locking member herein disclosed unapplied.

In the accompanying drawings, the casement frame F has associated therewith an outwardly swinging casement window W. A screen S, as illustrated in Figure 3, is adapted to be carried by and disposed over the frame F, said screen being applied as desired and preferably by swinging a marginal portion towards the improved applied operator as herein disclosed, the opposed marginal portion of the screen coacting with the frame to provide a fulcrum to facilitate such application. The lower member 1 of the screen S is provided with an elongated cut-out portion or notch 2 with which is associated a sliding plate 3 having a notch or recess 2'.

These features of the screen are particularly set forth in my application Serial No. 315,013 filed October 25, 1928, and for which reason a further detailed description and illustration thereof is believed to be unnecessary.

Anchored at the required position upon the lower member 4 of the casement window W is a bracket structure 5 provided with a pair of outstanding and vertically spaced arms 6. Extending between the outer extremities of the arms 6 and pivotally connected thereto, as at 7, is an outstanding arm 8 carried by an end portion of a sliding or operating bar 9. This bar 9 is straight from end to end and is tubular and of a cross sectional configuration to provide a T-slot 10. The restricted or stem portion a of the slot 10 is open at the under or bottom wall of the bar 9. Secured to the lower member 11 of the frame F is a bracket B preferably comprising a plate 12 which has direct contact with the member 11 and anchored thereto. The upper marginal portion of the plate 12 is defined by an outstanding plate 14. The outer longitudinal marginal portion of this plate 14 is upwardly offset, as at 15, to provide an inner shoulder b.

The bracket B provides a support for the applied screen S. The lower member 1 of

the bracket B seats upon the plate 14 inwardly of the shoulder b.

The plate 14, and more particularly the offset portion 15 thereof, is provided at a desired point therealong with the forwardly directed shelf or platform 16, the outer end portion c of which being semi-circular and concentric to an opening 17 disposed through said shelf or platform 16.

10 Snugly and rotatably fitting within this opening 17 is a cylindrical shank 18 which extends through the restricted portion or stem a of the T-slot 10 in the rod or bar 9. This shank 18 is provided with a cross-head

15 19 positioned within the enlarged head portion d of the T-slot 10 and of a width in excess of the width of the restricted portion or stem a of said slot.

The shank 18 in the present embodiment 20 of my invention terminates substantially flush with the under surface of the shelf or platform 16 and is continued by a reduced extension 20 angular in cross section and which is snugly received within an opening 25 21 provided within a plate 22 underlying the shelf or platform 16 and in close contact therewith. Threaded or otherwise engaged with the outer end of the extension 20 is a headed member 23 which serves to maintain 30 both the shank 18 and the plate 22 in applied position.

Radiating from the plate 22 is an arm 24 provided with a finger piece 25 positioned 35 beyond the periphery of the semi-circular portion c of the shelf or platform 16 whereby the shank 18 may be rotated at will for a purpose to be hereinafter referred to.

The head 19 hereinbefore referred to is 40 provided with diametrically opposed parallel straight edges 26 spaced apart a distance less than the space between the side walls 27 of the bar 9 but in excess of the width of the restricted portion or stem a of the slot 10.

When the shank 18 is adjusted to have 45 these straight edges 26 of the head 19 substantially parallel to the side walls 27 of the bar 9, said bar 9 has free endwise movement and at the same time has desired swinging movement. When it is desired, however, to 50 lock the bar 9 against endwise movement and thus effectively hold the window W in its desired adjusted position, it is only necessary to rotate the shank 18 through the instrumentality of the finger piece 25 and plate 22 to bring the curved portions 28 of the head 19 into binding contact with the side walls 27 of the bar 9, it being understood that said curved portions 28 are spaced apart a distance in excess of the space between the opposed faces of said side walls 27.

The outer end portion of the bar 9 has suitably secured thereto a handle 29 disposed on a curvature to facilitate engagement therewith of the digits of a hand.

55 When the window W is fully closed, the

arms 6 are disposed over the bracket B and through the cut-out portions or notches 2 and 4 and the bar 9 is in a position substantially in parallelism with the lower member 11 of the frame F.

70 When it is desired to open the window W outward swinging movement is imparted to the outer end of said bar 9 preferably by grasping with the fingers the handle 29. This swinging movement causes the opposite 75 end portion of the bar 9 to swing inwardly towards the frame F resulting in such leverage action to assure an easy initial outward swinging movement of the window W.

80 During this operation the shank 18 provides a pivot for the bar 9 and by sliding the bar 9 through the cut-out portions or notches 2 and 2' the window W may be adjusted to fully open position or at any desired point, and when adjusted as required the window is 85 effectively locked by imparting requisite turning movement to the shank 18 independently of the bar 9 by either push or pull upon the finger piece 25. To close the window W such 90 operation is reversed.

95 It is to be understood that as the window moves either outwardly or inwardly, the plate 3 will have requisite sliding movement thus assuring a substantial closing of the cut-out portion 2 of the member 1 at all 100 times to avoid the passage of flies, dust and the like therethrough. As before stated, this particular feature of the plate 3 is embodied in my pending application hereinbefore identified.

105 It is to be noted that the bar 9 is substantially shallow and flat on top and the construction of the bracket B is such that when the device is in applied position a minimum of space is occupied thereby so 110 that the portion of the applied device and more particularly of the bar 9 projecting above the lower member 11 of the frame F is negligible. This is of particular importance as it permits the screen S to be readily applied to the frame F when the upper marginal portion of said screen or a side marginal portion thereof is used as a fulcrum in connection with the frame F and swing 115 the screen S into desired applied or working position.

120 From the foregoing description it is thought to be obvious that an operator for a casement window constructed in accordance with my invention is particularly well adapted for use by reason of the convenience and facility with which it may be assembled and operated, and it will also be obvious that my invention is susceptible of some change 125 and modification without departing from the principles and spirit thereof and for this reason I do not wish to be understood as limiting myself to the precise arrangement and formation of the several parts herein shown 130.

in carrying out my invention in practice except as hereinafter claimed.

I claim:—

1. A closure fastener comprising a bracket, a pivot member rotatably carried thereby and including a head, an arm having a T-slot, the head of the pivot member being engaged within said T-slot, an attaching bracket operatively engaged with said arm, and means for rotating the pivot member independently of the arm, the head of the pivot member having portions engageable with the arm when the pivot member is so rotated to lock the arm against endwise movement.
- 15 2. A closure fastener comprising a bracket, a pivot member rotatably carried thereby and provided with a head, an arm having a T-slot in which the head of the pivot member is arranged, an attaching bracket operatively engaged with said arm, said head of the pivot member having a major diameter and a medium diameter, said medium diameter when disposed transversely of the arm permitting free sliding movement of the arm with respect to the pivot member, said head when its major diameter is angularly disposed with respect to the longitudinal axis of the arm engaging said arm to hold the same against endwise movement, and means for rotating the pivot member independently of the arm.
- 30 3. A closure fastener comprising a pivot member, means for rotatably supporting said pivot member, an operator arm slidably engaged with the pivot member, and a cross-head carrier by the pivot member, the extremities of said cross-head being engageable with the arm upon rotation of the pivot member for holding the arm against endwise movement with respect to the pivot member.
- 40 40 In testimony whereof I hereunto affix my signature.

THEODORE JOHNSON.
